Primary Examiner — Michael C Stout*Assistant Examiner* — Fitzgerald L Butac(74) *Attorney, Agent, or Firm* — Schneider IP Law LLC;
Laura Schneider(57) **CLAIM**

The ornamental design for a situational awareness robot, as shown and described.

DESCRIPTION

FIG. 1 is a top perspective view of the claimed design;
FIG. 2 is a bottom perspective view of the claimed design;
FIG. 3 is a front view of the claimed design;
FIG. 4 is a back view of the claimed design;
FIG. 5 is a right side view of the claimed design;
FIG. 6 is a left side view of the claimed design;
FIG. 7 is a top view of the claimed design; and,
FIG. 8 is a bottom view of the claimed design.
The broken lines show portions of a situational awareness robot which form no part of the claimed design.

1 Claim, 8 Drawing Sheets(56)
